GEORGE A. GAUTHIER, OF HARTFORD, CONNECTICUT, ASSIGNOR TO THE ARROW ELECTRIC COMPANY, OF HARTFORD, CONNECTICUT, A CORPORATION OF CONNECTICUT.

ELECTRIC-LAMP RECEPTACLE.

1,168,190.

Specification of Letters Patent. Patented Jan. 11, 1916.

Application filed December 30, 1913. Serial No. 809,568.

To all whom it may concern:

Be it known that I, GEORGE A. GAUTHIER, a citizen of the United States of America, and residing at Hartford, in the county of 5 Hartford and State of Connecticut, have invented a certain new and useful Improvement in Electric-Lamp Receptacles, of which the following is a specification.

My invention relates to electric lamp receptacles and particularly to lamp receptacles for sign plates or outlet boxes, the object of my invention being to provide improved means for mounting the usual screw shell lamp terminal on the receptacle body.

15 In the accompanying drawings, Figure 1 is an inverted plan of a sign receptacle of one type in which my invention is embodied; Fig. 2 is a vertical section on the line 2—2, Fig. 1; Fig. 3 is a plan view of 20 the receptacle; and Fig. 4 is a perspective showing the position of the metal parts, with the porcelain body omitted.

In sign receptacles, outlet box receptacles and the like which are exposed to weathering conditions and the action of fumes and 25 gases constantly discharged from furnace chimneys, discoloration, oxidation, etc., of the usual screw-shell lamp terminal rapidly takes place and it is frequently desirable to 30 replace the screw shell. In order to do this conveniently the shell must be fastened by screws accessible from the front of the receptacle and this has already been proposed. As heretofore constructed, these screws pass 35 through the base of the receptacle and take into nuts or the like which are insecurely held merely by wax or the like on the back of the porcelain. As a result, when the new screw shell has been arranged in position 40 and it is attempted to insert the holding screws, it is a common experience to find that the loosely held nut is not in register with the hole through the base and consequently the screw will not enter. Slight 45 pressure when the screw is bearing against the nut, and not threading into it, frequently forces out the wax and with it the nut, which is thus readily lost. For these and other reasons, it is a common experience 50 to find a new shell secured only by a single screw entering the wire terminal plate on the back of the receptacle—a condition wholly unworkmanlike and insecure, but resulting from the defects above noted.

55 In the present construction, I have elimi-

nated the danger of such practice, by providing a yoke or plate into which the securing screws for the screw shell take, and hold said yoke in position by means which are undisturbed on the removal of the screw shell. Consequently when the new shell is placed in position and the securing screws are passed through the base, they enter the threaded holes of the yoke without fail since the position of the yoke has been positively 60 maintained in registry with the holes in the receptacle base.

The present construction may be applied to various types of receptacles. The receptacle here shown comprises a cup shaped 70 body 10 with lugs 11 adjacent its lamp receiving end by means of which it may be mounted on a sign plate. The outer face of the diaphragm 12 which forms the bottom of the receptacle, is provided with parallel grooves 13, 14 for the reception of line wires. Recesses 15, 16 cut by the line wire grooves, form seats for the strap 17 and the yoke 18 respectively. Outwardly struck tongues 19 and 20 form terminals for the 80 line wires. Connection from strap 17 to the center contact 21 of the receptacle is secured through the screw 22 which holds both strap and center contact in place.

The yoke 18 is tapped at the ends of its 85 two legs to receive the screws 23, 24 which pass down through the washers 25 and base flanges 26 of the screw shell terminal 27. The screw shell is thus not only mechanically held in position on the receptacle but 90 also electrically connected to one of the line wires. The yoke is also tapped to receive the security screw 28 the head of which is seated in the well 29 below the base flange of the screw shell. A lug 30 may be formed 95 on one leg of the yoke to afford sufficient metal for the tap without unduly weakening the yoke. It is obvious that this construction enables the screw shell to be removed from the front of the receptacle by 100 loosening the screws 23, 24 while the yoke 18 is held by the security screw 28 in exact position to receive the screws 23, 24 when readjusted with the new screw shell.

The precise manner of fastening the yoke 105 in position may be varied in many ways and I do not limit my invention to the precise structure shown.

I claim as my invention:—

1. A lamp receptacle comprising an insu- 110

- lating base, a screw shell with base flange thereon, a wire terminal yoke, a plurality of screws passing downward through the base flange of said screw shell and insulating base and threaded into said yoke to mechanically and electrically connect said screw shell and yoke, in combination with a security screw lying below the base of screw shell and passing downward through 10 the insulating base of the receptacle and tapped into said yoke to hold the latter in position irrespective of the screw shell holding screws, substantially as described.
2. A lamp receptacle comprising an insulating base recessed on its outer face to form a well, a screw shell with holding flange seated in the bottom of said well, a current-carrying yoke plate mounted on the inner face of said base beneath said well, a plurality of screws passing downward through the holding flange of the screw shell and the base and taking into said yoke, in combination with a screw arranged in the well in the base and beneath the screw shell and passing downward through said base into engagement with the yoke to hold the latter 20 25

in fixed position to receive the screw shell securing screws.

3. A lamp receptacle comprising an insulating base recessed on its outer face to 30 form a well, a screw shell with holding flange seated in the bottom of said well, a current-carrying yoke plate mounted on the inner face of said base beneath said well, a plurality of screws passing downward 35 through the holding flange of the screw shell and the base and taking into said yoke, in combination with a screw arranged in the well in the base and beneath the screw shell and passing downward through said 40 base into engagement with the yoke to hold the latter in fixed position to receive the screw shell securing screws, said yoke-engaging screw being inaccessible in the completed fitting.

45
In testimony whereof I have signed my name to this specification, in the presence of two subscribing witnesses.

GEORGE A. GAUTHIER.
